PIANO ACTION

Charles R. Dowling, Newark, Ohio

Application August 16, 1954, Serial No. 449,829

6 Claims. (Cl. 84—240)

This invention relates to piano actions, the primary objects of the invention being to provide a piano action which is comparatively compact in its overall dimensions, and one which, when operatively installed in an associated piano, is readily accessible and easy to remove for the purposes of repair, adjustment and maintenance.

Another object of the invention is to provide a piano action composed of a relatively stationary frame, a system of key-actuated levers and an associated hammer so arranged and connected to form a unitary assembly which is characterized by its mechanical simplicity, accurately timed operation and unusual compactness, particularly in its height dimensions.

A further object is to provide a piano action which is formed to include a mounting post adapted to be attached to an associated action rail of a piano frame by a single, readily accessible screw, and wherein the post has pivotally mounted thereon a key-actuated whippen to which is directly hinged the shank of a hammer, the hinge employed being of such design as to cause the hammer to swing in one direction in unison with the whippen to strike an associated tuned piano string, and to enable the hammer to move in the opposite direction, independently of the whippen, out of engagement with the string following tune-producing contact therewith.

A still further object is to provide a piano action of the type indicated which includes in combination with the whippen and hammer elements a novel jack lever assembly whose function it is to cause the hammer hingedly mounted on the pivoted whippen to swing positively in unison with the whippen when the hammer is being moved into striking contact with an associated piano string, and wherein a release mechanism is provided in association with the jack lever assembly to cause the latter to assume a position releasing the hammer for rocking movement independently of the whippen on which it is carried, whereby to space the head of the hammer from said string immediately following its vibration-producing contact therewith and at the same time to return the hammer immediately to a position to be moved in unison with the whippen upon successive actuations of the associated piano key.

These and additional objects and advantages of the present invention will become more readily apparent by reference to the following description and the accompanying drawings, wherein:

Fig. 1 is a vertical transverse sectional view taken through a piano frame, and illustrating in side elevation the construction of the present piano action;

Fig. 2 is an enlarged fragmentary vertical sectional view disclosing the action at rest;

Fig. 3 is a vertical sectional view taken on the line 3—3 of Fig. 2;

Fig. 4 is a view similar to Fig. 2, but disclosing the position of the parts of the action immediately following key-striking actuation thereof;

Fig. 5 is a detail perspective view of the action in a raised position;

2

Fig. 6 is a detail sectional view disclosing the hinge union between the hammer shank and whippen bar of the action;

Fig. 7 is a detail vertical sectional view on the line 5 7—7 of Fig. 6;

Fig. 8 is a similar view through the key mounting and levelling means.

Referring to the mechanism illustrated in the drawings, and the various detail parts thereof by reference characters, my improved piano action is actuated by the usual finger-operated keys, one of which is shown at 10. As illustrated, the construction includes the usual horizontal and stationary frame-supported key bed rails 11 on which rests an end rail 12. At the front of the bed rails there is 15 stationarily arranged a key slip 13 and to the rear of the latter and carried by the end rail 12 is a horizontal front rail 14. Projecting upwardly from the front rail are the usual front pins 15 for key guidance, the upper surface of the front rail, adjacent to the pins, being provided with 20 front key cushions 16, which yieldably check key depression. The forward end of each key is equipped with the usual top covering 17 of ivory or the like and a front covering 18. A cooperative sharp key is shown at 19.

In rockably supporting the keys 10, each key, intermediately of its length, is formed with a slot 20 having downwardly tapering and converging walls. Each slot receives the stationary upper portion of a vertically disposed balance pin 21. The lower end of each pin 21 is threaded into openings provided therefor in the bed rails 11, end rail 12 and a balance rail 22. Intermediately of its length each pin 21 is formed with a fixed collar 23 which forms a base on which an associated key rests and fulcrums. The upper end of each pin projects above the key associated therewith and is squared for the reception 35 of a detachable turning wrench, not shown, whereby the pin may be raised or lowered in adjusting or levelling key action to obtain desired operation thereof and in a manner eliminating the use of shims and other removable raising and lowering means customarily employed in obtaining these adjustments.

The inner or rear end of each actuating key 10 rests normally, as shown in Figs. 1 and 2, on a key rest strip 25 of felt or the like. The strip is carried by a key rest rail 26, which may be hinged as at 27 to the key bed rail 11. The underside of the key rest rail 26 may be engaged with the upper end of a vertically movable, foot-pedal actuated post 28 which is slidably supported in connection with the rearmost of the bed rails 11, and may be operated to soften hammer action, as will be presently 50 explained.

Stationarily carried by the frame structure, not shown, of the piano and arranged adjacent to the rear or inner ends of the keys 10 is an action rail 29. The latter has its upper and forward longitudinally extending edge inwardly recessed at 30 to receive, in registry with the rear end of each key 10, the lower end of an upright mounting member or hammer assembly post 31. The lower part of the back face of each post 31 may be grooved to receive a positioning rib 32 formed with the vertical 55 face of the recess 30. A single fastening screw 33 is preferably employed in securely joining the lower end of each post 31 with the action rail 29 and to retain the same in its proper position thereon. The removal of this screw 35 enables the entire hammer action including its accompanying damper means, to be removed from the action rail as a unit.

Each of the hammer assembly posts 31 includes a vertically extending slot 34 in which is positioned for oscillatory movement in a vertical plane the inner reduced 60 end 34a of a bar-like whippen 35. A horizontal pivot pin 36 may be used in pivotally uniting each whippen with its associated post 31, so that the whippen may

oscillate freely in one direction in response to vertical motion imparted thereto by a key 10 and to respond to gravity in moving an opposite direction. The under surface of each whippen is recessed to receive a capstan cushion 37. The latter is normally engaged with an adjustable capstan 38 carried by and arising from the rear end of each key 10.

Thus, when the outer end of each key is depressed under finger pressure, the key so activated will rock vertically on the balance rail 22 and the collar 23 of the associated balance-rail-carried pin 21. This action causes the elevation of the rear end of the depressed key so that the capstan 38 thereof will engage the cushion 37 to tilt the whippen about its pivot axis 36 in a manner lifting the forward end thereof from the position thereof illustrated in Fig. 1 to that of Fig. 4.

Pivotedly mounted as at 39 on a bracket 40 carried by each whippen is the lower end of a hammer shank 41. The hammer shank extends substantially perpendicularly upwardly from the whippen and is provided at its lower part with a rigid forwardly and laterally projecting jack support 42 which is arranged so that its long axis is perpendicular to that of the hammer shank with which the jack support is either integrally formed or securely attached. Disposed between the under side of each jack support and the upper surface of the associated whippen is a coil spring 43, which serves normally to maintain the lower end of the hammer shank in contact with a cushioning pad 43a arranged on the flat upper surface of the whippen 35, so that the whippen and hammer shank carried thereby may operate under certain conditions as a rigid unitary construction.

The jack support 42 of my improved piano action is formed with a bifurcated forward end 44 for the reception of the intermediate portion of a lever-like pack 45, the latter being pivotally joined, as at 46, to the associated bifurcated end of the support 42. The lower end of each jack is positioned to engage a shoulder or upper step 47 of a buckskin or felt-lined notch 48 formed in the extreme forward end of each whippen 35.

It will be evident that when a key 10 is depressed the rear or inner end thereof is elevated as a result of the rocking of the intermediate part of the depressed key on the balance rail 22. This upward movement of the actuated key elevates the capstan 38 carried at the rear thereof. The capstan, through its engagement with the cushioned under surface 37 of the whippen 35 at a position forwardly of the pivot 36, rocks said whippen and the hammer shank 41, advancing the head 49, which is fixed on the upper end of each shank, into striking contact with the associated vertically disposed tuned wire string 50 of the piano. As long as the jack 45 remains in its position of engagement with the upper whippen shoulder or step 47, the hammer assembly, which includes the whippen, jack support, jack, and hammer shank and head, will function as a rigid or integral unit.

However, immediately after the hammer head strikes the string 50, further depressing movement of the key 10 in response to the playing touch of the musician, causes further rocking movement of the forward part of the whippen as a result of the lifting action of the capstan 38. The hammer shank, concomitantly with the head 49 striking the string 50, is further elevated with the whippen and the head returns to a position in slightly spaced relation to the string, as indicated by full lines in Fig. 4. In this operation a jack trip button or contact member 51 contacts the lower wedge-like part of a hammer stop or cam member 52 disposed on the forward face and at the upper end of the hammer-supporting mounting member or post 31. The button or contact member 51 of the hammer assembly is carried on the inner end of a rod 53 which is slidably mounted in a bearing opening 53a therefor formed in the thickened lower or butt part of the hammer shank 41. The inner end of this rod carries a connecting block 54 to which is

pivoted, as at 55, the upper end of the associated jack lever arm 45. As will be understood, the button 51, rod 53 and block 54 provide a plunger means operable to disengage the lower end of the arm 45 from the upper step or shoulder 47 of the whippen.

Thus, when the button 51 of the hammer assembly contacts the wedge stop 52 during upward swinging movement of the hammer shank 41, the button rides upwardly over the outer cam surface 52a of the stop 52 and the rod 53 is forced inwardly moving the block 54 therewith and rocking the associated jack arm 45 in a counter-clockwise direction as viewed in Figs. 1, 2 and 4, to disengage the lower end of the arm 45 from the upper step or shoulder 47. This action releases the hammer shank 41 and permits the same to rock a slight distance backwardly out of engagement with the string 50. In the same movement, the hammer shank 41 at the button 51 and the jack 45 are clamped firmly in the lower step or part of notch 48 to prevent any rebounding of the hammer head against the tuned string 50.

Also, during elevation of the outer end portion of the whippen under key-actuation, the inner end portion thereof is rocked downwardly, causing a cushioned face cam shoe 56 thereon to engage the head of an adjustable screw 57 carried by the lower end of an associated damper lever 58. The lever 58 is pivotally supported, as at 59, on the outer end of a forwardly directed extension 60 of the post 31. A wire spring 61 is used to apply a force to the lever 58 normally maintaining the damper pad 64 carried thereby in contact with the associated tuned string 50. The upper end of each lever 58 carries a vertical stem 62 on which is adjustably supported a damper head 63 having the pad 64 for vibration-damping engagement with its associated string 50.

When the key 10 is depressed, as shown in Fig. 4, the shoe 56 of the key-actuated whippen will be moved downwardly to an extent in which it fully contacts the head of the screw 57 of the associated damper lever 58, thereby rocking the latter about its pivot 59 to withdraw the damper head 62 slightly from vibration-arresting contact with the string 50. Such withdrawal takes place immediately prior to the engagement of the hammer head with the string and is maintained until the actuating key 10 is released.

After the key 10 has been released by the musician, the forward part of the whippen 35 descends gravitationally through rocking movement of the whippen about its pivot 36 on post 31. This action results in lowering the hammer mechanism to the normal position shown in Fig. 1. At this time the spring 43 and its associated wire spring 45a return the jack 45 to its normal engagement with the upper shoulder or notch 47 of the whippen. This re-seating of the jack takes place quickly upon key release and within approximately one-eighth of an inch of key travel, allowing quick repetition for a succeeding hammer contact with string 50 without requiring the key to be fully released or lifted to its extreme elevated rest position.

The post 28 in the usual manner, is connected to be actuated or elevated by the soft pedal, not shown, of the piano. The post 28, in turn, raises the hinged key rest strips 25 and 26 which are hinged, at at 27, to the rail 11. This operation serves to partially elevate the forward end of the key 10 and brings the action closer to the strings 50, shortening the hammer stroke and consequently softening the tone. By the same action the outer, finger-engaging ends of the keys 10 are lowered, and the operating travel thereof shortened.

In view of the foregoing, it will be evident that the present invention provides a simple yet efficient piano action in which the hammer, damper and jack elements thereof are compactly grouped to minimize vertical space requirements in a manner providing for a considerable reduction in overall height of the complete action. This end is achieved by arranging most of the lever components laterally of the hammer shanks rather than below

the same. In so doing, I am enabled to construct a piano of reduced height dimensions as compared with one containing a conventional action, making feasible the use of a smaller outer case.

It will also be noted that each complete hammer action, following removal of a registering key, may be quickly and conveniently detached from the action rail 29 merely by the removal of a single readily accessible screw.

It will be understood that the novel features of construction and arrangement of parts of the present invention may be embodied in other structural forms without departing from the spirit and scope of the invention as the same have been defined in the following claims.

I claim:

1. A unitary mechanical piano action comprising: a mounting member for detachable connection with a stationary frame element of a piano, a cam formation on said mounting member, a shouldered key-actuated whippen pivotally mounted on said member, a hammer having a shank and a string-striking head, means pivotally uniting one end of the hammer shank directly with an intermediate part of said whippen in a manner providing for bodily swinging movement of the hammer with said whippen when the latter is oscillated in an advancing direction to cause the head of the hammer mounted thereon to strike an associated tuned piano string, lever means pivotally carried by said shank and normally engaged with a shoulder of said whippen, and plunger means slidably carried by said hammer shank, said plunger means being disposed to contact the cam formation of said mounting member immediately following percussive contact of the hammer head with said string to release said lever means and produce independent limited return movement of said hammer about the axis of pivotal connection thereof with said whippen.

2. A unitary mechanical piano action comprising: a mounting member, means for detachably uniting said member and the piano action bodily carried thereby with a supporting piano frame, a key-actuated shouldered whippen pivotally mounted on said member, a hammer including a shank having a string-striking head on one end thereof, pivotal means mounting the opposite end of said shank directly on said whippen, said means producing movement of the hammer in unison with the whippen when the head of the hammer is moved into striking contact with an associated piano string; and means for causing positive independent reverse movement of the hammer relative to the whippen immediately following head contact with said string, said last-named means comprising a jack lever pivotally carried by said shank, said lever having one end thereof engaged normally with a shoulder on said whippen to cause the hammer to move in a string-striking direction in unison with said whippen, and plunger means movably carried by said shank and pivotally connected with said lever, said plunger means being engageable with said mounting member following string contact by said head to effect release of said lever from engagement with said whippen shoulder and to produce reverse swinging movement of said hammer in a direction spacing the head thereof from the associated string.

3. A unitary mechanical piano action comprising: a relatively stationary mounting member having a wedge formation thereon, a key-actuated whippen bodily carried by said member for pivotal movement thereon, said whippen being provided at one end thereof with a vertically offset shouldered portion, a hammer comprising a shank

and a string-striking head, means pivotally uniting the hammer shank at one end to said whippen, pivoted jack means carried by said hammer shank and having normally locked engagement with the shouldered portion of said whippen to retain said hammer positively for swinging movement with said whippen during forward movement of the hammer into striking contact with a piano string, a plunger slidably carried by said hammer shank and pivotally connected with said jack means, said plunger including a contact member engageable with the wedge formation of said stationary mounting member as said hammer reaches a string-striking position, said plunger being operable upon engagement of said contact member with said wedge formation to release said jack means from its normally locked engagement with the shouldered portion of said whippen and to produce positive, limited reverse movement of said hammer in a direction away from the associated piano string.

4. Apparatus as defined in claim 2, and wherein spring means are provided serving to yieldably resist turning movement of said hammer in response to forces applied thereto by said plunger means in rocking said hammer in a direction removing the head thereof from string engagement.

5. Apparatus as defined in claim 2, and wherein spring means are provided serving to yieldably resist turning movement of said hammer in response to forces applied thereto by said plunger means in rocking said hammer in a direction removing the head thereof from string engagement, and additional spring means cooperative with said jack lever and urging the same in a direction to maintain contact thereof with the whippen shoulder normally engaged thereby.

6. A unitary piano action comprising a single mounting post for attachment to a stationary frame element of a piano; a key-actuated whippen pivotally connected with said mounting post for swinging movement in a vertical plane, said whippen being formed at one end thereof with vertically offset upper and lower steps; a hammer including a string-striking head portion and a shank portion; means connecting the shank portion of said hammer with said whippen and providing for limited pivotal movement of said hammer with respect to said whippen;

7. A unitary piano action comprising a single mounting post for attachment to a stationary frame element of a piano; a key-actuated whippen pivotally connected with said mounting post for swinging movement in a vertical plane, said whippen being formed at one end thereof with vertically offset upper and lower steps; a hammer including a string-striking head portion and a shank portion; means connecting the shank portion of said hammer with said whippen and providing for limited pivotal movement of said hammer with respect to said whippen; a jack lever pivotally connected with the shank portion of said hammer and having an end normally engaging the upper step of said whippen, said jack lever serving to support said hammer for unified swinging movement with said whippen to a string-striking position; cam means carried on said mounting post; and plunger means slidably carried by the shank portion of said hammer and pivotally connected with said jack lever, said plunger being arranged on the shank portion of said hammer to engage said cam means as said hammer reaches its string-striking position and being movable upon engagement with said cam means to rock said jack lever to disengage the end thereof from the upper step of said whippen and to rock said hammer backwardly away from its string-striking position.

8. A unitary piano action comprising a single mounting post for attachment to a stationary frame element of a piano; a key-actuated whippen pivotally connected with said mounting post for swinging movement in a vertical plane, said whippen being formed at one end thereof with vertically offset upper and lower steps; a hammer including a string-striking head portion and a shank portion; means connecting the shank portion of said hammer with said whippen and providing for limited pivotal movement of said hammer with respect to said whippen; a jack lever pivotally connected with the shank portion of said hammer and having an end normally engaging the upper step of said whippen, said jack lever serving to support said hammer for unified swinging movement with said whippen to a string-striking position; cam means carried on said mounting post; and plunger means slidably carried by the shank portion of said hammer and pivotally connected with said jack lever, said plunger being arranged on the shank portion of said hammer to engage said cam means as said hammer reaches its string-striking position and being movable upon engagement with said cam means to rock said jack lever to disengage the end thereof from the upper step of said whippen and to rock said hammer backwardly away from its string-striking position.

9. A unitary piano action comprising a single mounting post for attachment to a stationary frame element of a piano; a key-actuated whippen pivotally connected with said mounting post for swinging movement in a vertical plane, said whippen being formed at one end thereof with vertically offset upper and lower steps; a hammer including a string-striking head portion and a shank portion; means connecting the shank portion of said hammer with said whippen and providing for limited pivotal movement of said hammer with respect to said whippen; a jack lever pivotally connected with the shank portion of said hammer and having an end normally engaging the upper step of said whippen, said jack lever serving to support said hammer for unified swinging movement with said whippen to a string-striking position; cam means carried on said mounting post; and plunger means slidably carried by the shank portion of said hammer and pivotally connected with said jack lever, said plunger being arranged on the shank portion of said hammer to engage said cam means as said hammer reaches its string-striking position and being movable upon engagement with said cam means to rock said jack lever to disengage the end thereof from the upper step of said whippen and to rock said hammer backwardly away from its string-striking position.
